UNITED STATES PATENT OFFICE.

CLAUD PORTER, OF DE SMET, SOUTH DAKOTA.

TWO-POINT-CONNECTER LIGHT PLUG.

Application filed June 17, 1922. Serial No. 569,131.

To all whom it may concern:

Be it known that I, CLAUD PORTER, a citizen of the United States of America, residing at De Smet, in the county of Kingsbury and State of South Dakota, have invented certain new and useful Improvements in Two-Point-Connector Light Plugs; and I do hereby declare that the following is a full, clear, concise, and exact description of the invention, such as will enable others skilled in the art to which it appertains to make and use the same.

This invention relates to electric lighting systems and has special reference to an automobile lighting system.

More particularly the invention relates to a grounding plug for such systems.

It is a well known fact that in many instances headlights of an automobile are connected up in series to the source of electricity, a return wire being used so that the entire is a wire system and without grounds. Also, it is a well known fact that in such a system the burning out of one lamp prevents current passing through the other.

One important object of the present invention is to provide an improved means, in such a lighting system, whereby the burning out of one lamp will not prevent the use of the other.

A second important object of the invention is to provide an improved adaptor, including a grounding plug of novel construction, for utilization in such a system in such manner that either of the lamps may be grounded at will.

A third important object of the invention is to provide a novel form of grounding plug carrying a small grounding switch housed within the outer dimensional limits of the plug, which switch may be moved to ground one of the conductors at will.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a longitudinal section through an adaptor of improved construction showing the same in position in a supporting tube.

Figure 2 is a side elevation of the adaptor plug removed from the adaptor.

Figure 3 is a section on the line 3—3 of Figure 2.

Figure 4 is a section on the line 4—4 of Figure 3.

Figure 5 is a diagrammatical view showing one form of circuit connections employing grounding switches.

Figure 6 illustrates a second form of such connection.

In the embodiment of the invention herein disclosed there is provided a plug which has a cylindrical body 10 formed of hard rubber, porcelain, or other similar insulating substance. Through this body extends a pair of longitudinal passages, or openings 11 wherein are fitted conductor members. Each of these members has a tubular end 12 for the reception of the circuit wires. At its other end each conductor terminates in a contact pole, or member 13 engageable by the contacts of a two-pole lamp base when the latter is inserted in a shell 14 mounted thereon. This shell detachably receives the plug, a ground contact and plug securing pin 15 sliding transversely of the plug between the openings 11 for this purpose. This pin extends beyond the plug and fits the bayonet slots 16 of the shell, the other end of the shell being provided with similar bayonet slots for engaging pins on the lamp base. At one end of the opening 18 through which the pin slides is a circular recess 19 and on the end of the pin which passes through this recess is a washer, or collar 20 between which and the bottom of the recess 19 is a coil compressor spring 21 surrounding said pin 15. By this means the pin is constantly urged longitudinally. Opposite the recess 19 there is provided a second recess 22 having diverging sides 23. The pin 15 passes through the smaller end of this recess and on this end pin is a washer 24 which forms a bearing washer for a switch arm 25 fixed on said pin. On the free end of this switch arm is a ball 26 which is adapted to seat either in a cup-shaped depression 27 or in an opening 28 which leads from the wide end of the recess 22 into one of the openings 11 so that a portion of the conductor is exposed through this opening. It is obvious that when seated in this opening, as will be shown in Figure 4, the ball 26 contacts with said conductor and consequently electrical

connection is established between the pin 15 and said conductor, the arm 25 and ball 26 being of conductive material. The shell 14 is supported in the lamp housing, or 5 casing, by means of a spring bolt 29 which passes through a suitable part of the lamp housing, not shown, and through a bracket 30 fixed on the shell 14. An insulating shell 31 is also provided on the plug and serves 10 as a lead-in tube for the wires conducting the electricity, to the contact members 12. It will now be seen that by shifting the arm 25 to one position or the other the plug may be used either as an ordinary contact 15 plug or one of the wires may be grounded. Consequently, when these plugs are used for the headlights, or other series connected lights any light may be grounded at will. For instance, in such a construction as shown 20 in Figure 5 there is provided a source of electricity 32 from which leads a wire 33 to a lamp 34. From the lamp 34 the wire 35 leads to a second lamp 36 from whence a wire 37 leads back to the source 32. This 25 is the ordinary series connected over-wire lighting system, but in such a system, if one of the lamps burns out, as for instance, the lamp 36, the plug which is here indicated in general as at P, can be set to ground the wire 37 while the plug for the lamp 34 can be set to ground the wire 35, this 30 plug being indicated at P'. Under these circumstances, current will flow from the source 32 through the wire 33, lamp 34, plug 35 P' to the ground. From the ground current will flow through the plug P, and wire 37 back to the source 32. In Figure 6 one 35 side of the generator, or source 32 is grounded through a wire 38 and the lamps are connected to the other side of the source in multiple through wires 39 and 40 each lamp being normally grounded to the machine as indicated at 41 through wires 42. In the 40 event of either of the wires 42 becoming broken as frequently happens, the plug P, or P' may be properly adjusted to meet 45 the condition by establishing a ground close to the lamp.

There has thus been provided a simple 50 and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention what is claimed as new, is:—

1. A grounding plug comprising an insulating body, a pair of spaced conductors extending longitudinally through said body, a 65 ground contact pin extending transversely

of the body in spaced relation to the conductors, and conductor means carried by the pin and movable into and out of engagement with one of said conductors.

2. A grounding plug comprising an insulating body, a pair of spaced conductors extending through the body, said body having a recess in one side opening at one end to one of said conductors to expose a portion of the same, a ground contact pin at the other end of said recess, and a conductor member in said recess and having one end secured to the contact pin and the other end movable into and out of engagement with the exposed conductor portion. 70 75 80

3. A grounding plug comprising an insulating body having a lateral recess and provided with a pair of longitudinal passages, said recess being provided at one end with a cup shaped depression and an opening leading into one of the longitudinal openings, a grounding pin at the end of the recess opposite the depression, an arm housed in said recess and having one end fixed to said pin, a ball on the other end of said arm movable for selective positioning in the depression or recess opening, and a pair of conductors leading through the pair of openings, one of said conductors being engageable by said ball. 85 90 95

4. A grounding plug comprising an insulating body having a lateral recess and provided with a pair of longitudinal passages, said recess being provided at one end with a cup shaped depression and an opening leading into one of the longitudinal openings, a grounding pin at the end of the recess opposite the depression, an arm housed in said recess and having one end fixed to said pin, a ball on the other end of said arm movable for selective positioning in the depression or recess opening, a pair of conductors leading through the pair of openings, one of said conductors being engageable by said ball, and spring means urging said ball inward. 100 105 110 115

5. A grounding plug comprising an insulating body having a lateral recess and provided with a pair of longitudinal passages, said recess being provided at one end with a cup shaped depression and an opening leading into one of the longitudinal openings, a grounding pin at the end of the recess opposite the depression, an arm housed in said recess and having one end fixed to said pin, a ball on the other end of said arm movable for selective positioning in the depression or recess opening, a pair of conductors leading through the pair of openings, one of said conductors being engageable by said ball, said contact pin being slideable transversely through the plug and the latter having a second recess surrounding the pin and opposite the first re- 120 125 130

cess, a washer on said pin at the outer end of the second recess, and a compression spring surrounding the pin between the washer and the bottom of the second recess.

- 5 6. In combination, a plug having a cylindrical insulating body provided with a pair of longitudinally extending openings, conductors located in said openings and each having one end adapted to receive a 10 conductor wire and its other end forming a contact pole to engage a contact on a lamp base, said body having a recess in one side having tapering sides and provided at its larger end with a cup shaped 15 depression at one side and an opening communicating with one of the pair of longitudinal openings to expose one of the conductors, said body having a second recess opposite the smaller end of the first recess

and communicating therewith through an 20 opening extending between the conductors, a ground contact and plug securing pin 25 slideable in the opening between said recesses and having its ends projecting from the body to engage the bayonet slots of a socket, a washer on the pin in the second recess, a spring surrounding the pin between said washer and the recess bottom, a conductor 30 arm on the opposite end of the pin and extending longitudinally of the first recess, 35 a ball on the free end of said arm adapted for selective seating in the depression and against the exposed conductor, and a lamp base receiving sleeve carried on the end of the body adjacent the contact pole ends of the conductors.

CLAUD PORTER.
